UNITED STATES PATENT OFFICE.

WILLIAM SCOTT, OF GLASGOW, SCOTLAND.

STEAM-TRAP.

1,310,507.

Specification of Letters Patent. Patented July 22, 1919.

Application filed October 30, 1918. Serial No. 260,300.

To all whom it may concern:

Be it known that I, WILLIAM SCOTT, of 22 Waverley Gardens, Crossmyloof, Glasgow, Scotland, a subject of the King of 5 Great Britain, have invented a certain new and useful Improved Steam-Trap, of which the following is a specification.

This invention relates to an improved and simplified construction of steam trap of the 10 thermostatic class having inner and outer members composed of metals having different ratios of expansion and contraction under changes in temperature.

The main feature of the invention is that 15 the inner member, into which the steam enters, is provided with a valve at its end this valve having on, or in connection with it, a cup part or extension so made as to prevent the steam having direct access to 20 the valve and the valve seat which latter is, preferably, formed on, or in, a removable coupling fitted in, or to, the outer member. The construction of the device, as a whole, is very simple and therefore inexpensive and 25 can be readily fitted in steam pipe lines.

The improved trap is shown, by way of illustration or example, on the accompanying sheet of drawings, whereon:

Figure 1 is a vertical section of the trap 30 and

Fig. 2 an outside elevation thereof.

The trap shown comprises an outer tube *a*, preferably made of iron or steel, and an inner tube *b*, preferably made of copper or 35 brass, the inner tube being screwed, or otherwise fitted, at one end, in a cap *c* at the top of the outer tube and, at the other end, having an internal plug *d* to which a cone or like valve *e* is screwed this valve having a 40 cylindrical extension or cup *e*¹ which surrounds the inner tube for a short distance, an annular chamber or space being left between the cup and the inner tube. The end of the inner tube, within the said cup, has 45 a series of holes *f* through which the water or steam can pass. The outer tube has also a bottom cap *g* into which is removably inserted a pipe coupling *h* (for connection to the drain) having a central passage *j* whose 50 upper lip *j*¹ serves as a seat for the conic valve. A number of interchangeable couplings may be used to suit the different drain pipe connections and to provide different valve seats *j*¹.

55 With this construction of trap the tube *b* can be suitably connected at the lowest part

of a pipe line so that water of condensation can flow, by gravity, thereinto as indicated by the arrow at *x*. Steam can also enter the tube. The water collecting in the 60 tube *b* passes out by the holes *f* and fills the cup *e*¹. Water overflowing from the cup collects at the bottom of the tube *a* and is drained away (in direction indicated by arrow *y*) whenever the valve *e* is opened, in 65 known manner, owing to the differential action of the metals composing the tubes *a*, *b*.

Whenever the valve opens, the steam 70 ejecting the water and escaping through the holes *f*, passes into the cup *e*¹ (which may be partially or wholly filled with water) and has not direct access to the face of the valve *e* and the valve seat *j*¹ with the result that these parts are not so liable to wear away. 75

The trap is exceedingly simple in construction, the parts can be readily assembled, and the trap, when assembled, can be readily fitted in a pipe line or elsewhere. The trap can be used in certain cases as a 80 thermostatic valve.

Having now fully described my invention what I claim and desire to secure by Letters Patent is:—

1. A steam trap, operated thermostatically, comprising an outer member, an inner member capable of movement relatively to the outer member, a valve on the end of the inner member and movable therewith and a seat for said valve on the outer member, the 90 valve having a hollow extension located between the inner and outer members and means whereby steam can pass through the inner member into the hollow extension and thereafter into the outer member. 95

2. A steam trap, operated thermostatically, comprising an outer hollow member, an inner hollow movable member, a conical valve at the end of the inner member and movable therewith and a seat for said valve, the 100 valve having a hollow extension located between the inner and outer members and means whereby steam can pass through the inner member into the hollow extension and thereafter into the outer member.

3. A steam trap, operated thermostatically, comprising an outer hollow member, an inner hollow movable member, a conical valve removably secured at the end of the inner member and movable therewith and a 110 circular seat for said valve, the valve having a hollow extension located between the

inner and outer members and means whereby steam can pass through the inner member into the hollow extension and thereafter into the outer member.

5. 4. A steam trap, operated thermostatically, comprising an outer tube, an inner steam tube, a conic valve, with tubular extension, at the end of the inner tube, a seat for said conic valve, means for the passage 10 of steam from the inner tube to said extension and a seat for said valve said seat being supported from the outer tube.

5. A steam trap, operated thermostatically, comprising an outer tube, an inner 15 steam tube capable of movement relatively

to the outer member, a conic valve at the end of and movable with the inner tube, said valve having a cylindrical extension located between the inner and outer tubes, means for the passage of steam from the inner tube to said extension and a seat for said valve said seat being on a removable coupling secured to the outer tube. 20

In testimony whereof I affix my signature in presence of two witnesses.

WILLIAM SCOTT.
